PAPERMAKING APPARATUS

Benjamin E. Teale, Dalton, Mass.

Application June 21, 1950, Serial No. 169,352

3 Claims. (Cl. 92—44)

1

This invention relates to paper making apparatus and is directed more particularly to improvements in slice construction adapted for use in connection with the Fourdrinier wire of a paper machine.

The principal objects of the invention are directed to the provision of slice apparatus which is constructed and arranged in a novel manner so as to facilitate economy in manufacture and assembly and which may be readily and easily associated with a paper machine.

As a special feature of the invention the slice construction is adjustable back and forth so that it may be positioned as desired relative to an element of the paper machine such as for instance another slice, head box or the like.

According to another novel feature of the invention the construction is such as to provide rigidity so that the free edge of the slice plate may be adjusted relative to the Fourdrinier wire and the adjustment maintained.

To the above cited and other ends and with the foregoing and various other novel features and advantages and other objects of my invention as will become more readily apparent as the description proceeds, my invention consists in certain novel features of construction and in the combination and arrangement of parts as will be hereinafter more particularly pointed out in the claims hereunto annexed and more fully described and referred to in connection with the accompanying drawings wherein:

Fig. 1 is a side elevational view of the bracket and slide arrangement of the slice construction of the invention.

Fig. 2 is a sectional elevational view on the line 2—2 of Fig. 1 and Fig. 3 is a sectional elevational view on the line 3—3 of Fig. 2.

Referring now to the drawing more in detail, the invention will be fully described.

Elongated side plates are represented by 2 which may extend along the paper machine at opposite sides of the Fourdrinier wire.

Elongated plates 4 are secured to outer sides of plates 2 by any suitable means and are formed so as to cooperate with said plates 2 to provide elongated T-slots as shown, which are disposed horizontally. Brackets 6 are provided which are slidable along the members 4. Bolts having heads 8 in the T-slots extend through the brackets 6 and have nuts 10 on outer ends thereof for securing the brackets in adjusted positions.

The brackets 6, as will appear, support the slice structure and they may be secured to the side plates to locate the slice as may be desired relative to other units of the machine.

Boxes 12 are adjustable up and down in the brackets 6 and adjusting screws 14 in threaded engagement with said brackets engage lower sides thereof to adjust the boxes up and down. Hand wheels 16 are fixed on the said screws 14

2

and locking members 18 are provided on said screws.

The boxes 12 are split, as shown, and receive opposite end portions of a tubular support 20. Screws 22 in engagement with upper portions of the block 12 are provided for clamping the support 20 in the boxes and is provided with a manually engageable member 24.

Slice brackets 26 are provided on the support which are split, as shown. Screws 28 in engagement with said brackets are provided for clamping the brackets to the support and have hand wheels 30 for turning the same.

Keys such as 32 are associated with the support 20 and brackets 26, as shown. The brackets 26 may be moved along the support to adjusted positions and secured therein by the screws 28. A keyway 34 for the keys 32 may if desired extend along the support 20.

Relatively diverging arms 36 and 38 extend from the brackets 26. An elongated reinforcing member 40 and a slice plate 42 are secured to the bracket arms 36 by bolts 44 or the like. The slice plate 42 will be formed from relatively thin sheet metal and the member 40 will be relatively more rigid to reinforce the upper edge of said plate 42.

Blocks 46 are secured to the lower marginal edge portion of the plate 42 and are arranged to provide slots therebetween, as shown. Adjusting screws 48 in the arms 38 of the brackets, have heads 50 disposed in said slots and hand wheels 52 are in threaded engagement with upper ends of said screws 48. Lock nuts 54 are provided on the screws 48 and are disposed in slots 56 provided in the outer ends of arms 38.

As will be seen the lower longitudinal edge of the plate 42 may be adjusted relative to the Fourdrinier wire by means of the screws 48 to obtain the desired functioning of the slice. The adjustment is secured by the lock nuts.

The longitudinal support may be oscillated in one direction or the other and secured in adjusted positions by the screw 22 whereby the angle of the plate relative to the Fourdrinier wire may be as desired.

The brackets 6 and slice apparatus may be moved back and forth to locate the slice relative to other units of a paper machine as may be desired.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview of equivalency of the appended

claims are therefore intended to be embraced therein.

What it is desired to claim and secure by Letters Patent of the United States is:

1. The combination with transversely spaced elongated horizontal side plates of a paper machine of a slice construction adapted for adjustment along said plates to position the slice plate thereof angularly with its lower edge positioned relative to a Fourdrinier wire which may be disposed between lower edges of said side plates comprising, elongated guide plates extending longitudinally of and secured to said side plates cooperating therewith providing elongated horizontal guideway slots, brackets slideable relative to said plates and having portions slideable in said slots and means for securing said brackets thereto in adjusted positions, boxes slideable up and down vertically in said brackets, manually engageable means threadedly engaging said brackets for elevating and supporting said boxes, said boxes provided with aligned horizontal bores, a transverse support having opposite ends rotatably adjustable in said bores and means for clamping said support in said bores, separate slice plate brackets rotatable on said support and means releasably holding said slice plate brackets in spaced relation on said support and against rotation relative thereto, said slice plate brackets provided with elongated upper and lower arms extending radially away from said support and having outer relatively spaced ends, an elongated slice plate extending between said side plates having an upper longitudinal edge portion secured to outer ends of the upper arms of the slice plate brackets, and separate manually adjustable connections between said lower arms and lower longitudinal edge portion of said slice plate, all adapted and arranged whereby said slide construction may be secured in adjusted positions along said side plates and said support may be rotated to adjusted positions to position said slice plate at various angles and the lower edge of said slice plate may be adjusted relative to a Fourdrinier wire disposed adjacent lower edges of said side plates.

2. The combination with transversely spaced elongated horizontal side plates of a paper machine of a slice construction adapted for adjustment along said plates and to position the slice plate thereof angularly and its lower edge positioned relative to a Fourdrinier wire which may be disposed between lower edges of said side plates comprising, plates extending longitudinally of and secured to said side plates cooperating therewith providing elongated horizontal guideway slots, brackets slideable relative to said plates and having portions slideable in said slots and means for securing said brackets thereto in adjusted positions, boxes slideable up and down vertically in said brackets, manually engageable means threadedly engaging said brackets for elevating and supporting said boxes, said boxes provided with aligned horizontal bores, a transverse support having opposite ends rotatably adjustable in said bores and means for clamping said support in said bores, separate slice plate brackets rotatable on said support and means releasably holding said slice plate brackets in spaced relation on said support and against rotation relative thereto, said slice plate brackets provided with elongated upper and lower arms extending radially away from said support and

having outer relatively spaced ends, an elongated slice plate extending between said side plates having an upper longitudinal edge portion secured to outer ends of the upper arms of the slice plate brackets, and separate manually adjustable connections between said lower arms and lower longitudinal edge portion of said slice plate, all adapted and arranged whereby said slide construction may be secured in adjusted positions along said side plates and said support may be rotated to adjusted positions to position said slice plate at various angles and the lower edge of said slice plate may be adjusted relative to a Fourdrinier wire disposed adjacent lower edges of said side plates, said manually engageable means including screw members in engagement with said boxes.

3. The combination with transversely spaced elongated horizontal side plates of a paper machine of a slice construction adapted for adjustment along said plates and to position the slice plate thereof angularly and its lower edge positioned relative to a Fourdrinier wire which may be disposed between lower edges of said side plates comprising, elongated guide plates extending longitudinally of and secured to said side plates cooperating therewith providing elongated horizontal guideway slots, brackets slideable relative to said plates and having portions slideable in said slots and means for securing said brackets thereto in adjusted positions, boxes slideable up and down vertically in said brackets, manually engageable means threadedly engaging said brackets for elevating and supporting said boxes, said boxes provided with aligned horizontal bores, a transverse support having opposite ends rotatably adjustable in said bores and means for clamping said support in said bores, separate slice plate brackets rotatable on said support and means releasably holding said slice plate brackets in spaced relation on said support and against rotation relative thereto, said slice plate brackets provided with elongated upper and lower arms extending radially away from said support and having outer relatively spaced ends, an elongated slice plate extending between said side plates having an upper longitudinal edge portion secured to outer ends of the upper arms of the slice plate brackets, and separate adjustable connections between said lower arms and lower longitudinal edge portion of said slice plate, all adapted and arranged whereby said slide construction may be secured in adjusted positions along said side plates and said support may be rotated to adjusted positions to position said slice plate at various angles and the lower edge of said slice plate may be adjusted relative to a Fourdrinier wire disposed adjacent lower edges of said side plates, said connections including screw members movable axially in the lower arms of the slice plate brackets having heads in slots provided on said slice plate and manually engageable members in engagement with said screw members.

BENJAMIN E. TEALE.
